(57) **CLAIM**

The ornamental design for an electronic document reader, as shown and described.

DESCRIPTION

FIG. 1 is a front, right side, and bottom side perspective view of an embodiment of an electronic document reader of the present design;

FIG. 2 is a top side elevational view of the electronic document reader of FIG. 1;

FIG. 3 is a bottom side elevational view of the electronic document reader of FIG. 1;

FIG. 4 is a right side elevational view of the electronic document reader of FIG. 1;

FIG. 5 is a left side elevational view of the electronic document reader of FIG. 1;

FIG. 6 is a front elevational view of the electronic document reader of FIG. 1;

FIG. 7 is a rear elevational view of the electronic document reader of FIG. 1; and,

FIG. 8 is a rear, left side, and bottom side perspective view of the electronic document reader of FIG. 1.

The broken lines shown in the drawings are for the purpose of illustrating unclaimed portions of the electronic document reader and form no part of the claimed design.

1 Claim, 6 Drawing Sheets
